C. H. KASCH.

PINTLE,

FILED MAR. 22, 1922.

UNITED STATES PATENT OFFICE.

CHARLES H. KASCH, OF DAVENPORT, IOWA.

PINTLE.

Application filed March 22, 1922. Serial No. 545,911.

(FILED UNDER THE ACT OF MARCH 3, 1883, 23 STAT. L., 625.)

To all whom it may concern:

Be it known that I, CHARLES H. KASCH, a citizen of the United States, and a resident of Davenport, county of Scott, and 5 State of Iowa, have invented an Improvement in Pintles, of which the following is a specification.

The invention described herein may be used by the Government, or any of its officers or employees in prosecution of work for 10 the Government, or by any other person in the United States, without payment to me of any royalty thereon.

My invention relates to a pintle which 15 has been designed, primarily, for use with the pintle bearing of a gun or limber.

The main object of my invention is the provision of a pintle which will hold the lunette without danger of jarring open during travel over rough roads and which will 20 not be so battered or burred by blows from the lunette as to interfere with the proper operation of the latch.

With the foregoing and other objects in 25 view, my invention resides in the novel arrangement and combination of parts and in the details of construction hereinafter described and claimed, it being understood that changes in the precise embodiment of 30 the invention herein disclosed may be made within the scope of what is claimed without departing from the spirit of the invention.

A practical embodiment of the invention 35 is illustrated in the accompanying drawing, wherein:

Fig. 1 is a view in side elevation of a pintle constructed in accordance with my invention;

Fig. 2 is a similar view partly in longitudinal section;

Fig. 3 is a rear elevation of the pintle body and

Fig. 4 is a perspective of the latch.

Referring to the drawing by numerals of 45 reference:

I provide a pintle body 1 formed at its rear end with a reduced headed shank 2, adapted for assembling with any limber

equipped to take a standard pintle, and a hooked forward end 3, the end of the hook 50 provided with a recess 4.

The main body portion of the pintle has an upwardly extending portion 5 bored longitudinally and having a longitudinal groove 5^a communicating with the bore at 55 its lower portion and a longitudinal slot 5^b communicating with the bore at the top thereof.

A latch 6 is mounted for reciprocatory movement longitudinally of the bore and is 60 formed with a depending rib to fit into the groove 5^a having a nose 6^a adapted to seat in the recess 4 when the latch is in its forward or closed position, a barrel 6^b for engagement with the bore, an upstanding rib 6^c for engagement in the slot and a knurled hand engaging portion 6^d by which the latch 65 may be manually forced to its rearmost position.

The latch member 6 is provided with a 70 socket opening at its rear face in which is seated the forward end of a resilient element, such as the coiled spring 7 housed in the bore and having its rear end seated in a socket formed in a screw plug 8 by means 75 of which the rear end of the bore is closed and through which the spring is tensioned. The plug may be locked in place, if desired, by a pin 9 positioned in an aperture formed transversely of the portion 5 and 80 communicating with the bore near its rear end.

I claim:

1. A pintle, including a body formed with a reduced headed shank at its rear end; a 85 hook at its forward end, the end of the hook provided with a recess; an upwardly extending portion provided with a longitudinal bore, a longitudinal groove communicating with the bottom of the bore and a 90 longitudinal slot communicating with the top of the bore; a latch member reciprocal in the bore and having lower and upper ribs to engage the groove and slot, respectively, and a nose for engagement with the recess; 95 a spring housed in the bore and normally

holding the latch in its forward position and means for closing the rear end of the bore and tensioning the spring.

2. A pintle, including a body formed with a reduced headed shank at its rear end; a hook at its forward end, the end of the hook provided with a recess; an upwardly extending portion provided with a longitudinal bore, a longitudinal groove communicat-

ing with the bottom of the bore and a longitudinal slot communicating with the top of the bore; a latch member reciprocal in the bore and having lower and upper ribs to engage the groove and slot respectively, and yieldable means for normally holding the latch member in forward position.

CHARLES H. KASCH.
